UNITED STATES PATENT OFFICE.

BEN CLIFFORD BLACKMON, OF DALLAS, TEXAS.

SUPPORT FOR COLLAPSIBLE CONTAINER TUBES.

Application filed June 30, 1925. Serial No. 40,558.

To all whom it may concern:

Be it known that I, BEN CLIFFORD BLACKMON, a citizen of the United States, residing at Dallas, in the county of Dallas and 5 State of Texas, have invented certain new and useful Improvements in Supports for Collapsible Container Tubes, of which the following is a specification.

The present invention relates to collapsible tube holders and more particularly to 10 such holders which provide for the dispensing of plastic material therefrom such as tooth paste, shaving cream and the like.

The principal purpose of the present invention is to provide a holder of this character wherein collapsible tubes or containers 15 may at all times be retained in available access to the user of the contents thereof and one which will accommodate tubes of various sizes.

A further object of the present invention is to provide a valve or closure attachment 20 for such holders, whereby when the tube is placed within the holder, the tube's cap 25 may be removed and the valve substituted therefor in order to prevent any contamination of the exposed uncovered paste contained within the tube.

Other objects will be hereinafter obvious 30 when having reference to the following specification taken in connection with the accompanying drawings in which:

Figure 1 is a side elevational view of the 35 improved holder embodying the present invention,

Figure 2 is a front elevation thereof, and

Figure 3 is a detail perspective view of the valve or tube closure.

Reference now being had to the accompanying drawings wherein like and corresponding parts are designated by similar reference characters throughout the several views, the numeral 1 indicates the holder which is preferably made from a single piece 45 of sheet metal having upturned side walls and an end wall 1' which latter is provided with a recess for the reception of the forward or dispensing end of the collapsible tube A. Formed with and extending from 50 one end of this holder is an extension 3, which latter may be provided with an opening for the reception of a nail or peg 4 driven within the wall or similar vertical support from which the holder is to be suspended. The lower or forward end of this 55 holder is provided with supporting legs 2

which legs are for the purpose of elevating or retaining the holder and the tube carried thereby in spaced relation from the wall or other support upon which the holder is mounted whereby ready access may be gained to the paste ejecting end of the tube. Whereas in the drawings I disclose this holder as being suspended upon a wall or similar vertical support it is of course to be understood that it may rest upon a table or other flat surface.

When using this holder a collapsible tube A containing tooth paste or shaving cream is placed within the side walls of the holder and the forward end of the tube rests within the wall 1' of the holder. This wall 1' of the holder is provided with a segmental clamping means 9 as is better illustrated in Figure 2 which engages over the tube for holding the latter in locked position. A collapsing key is slidably and rotatably mounted within the side walls of the holder and which key is adapted to engage the bottom portion of the tube A whereby upon rotation of this key the tube will be caused to be collapsed and the plastic material contained therein will be ejected from the mouth or nozzle end of the tube. By manually turning the handle 2' the tube collapsing key will be rotated whereby the desired amount of paste contained within the tube may be ejected therefrom, but when the required amount of paste has been ejected from the tube it is most desirable to protect the exposed portions of the paste remaining in the mouth or ejecting end of the tube. Ordinarily, these collapsible tubes are provided with caps, closing the ejecting ends of the tubes, but as these caps often become lost, I provide a valve or closure for the ejecting end of the tube, which valve or closure is permanently affixed to the tube holder. Secured to and projecting from the lower forward end of the holder is a flat piece of metal 5 to which is to be attached the tube closure.

The outer end of this piece of metal is bent downward in the position shown in Figure 1 to provide a lip 6 and to this lip is pivoted a similar flat piece of metal 7 which as illustrated in Figure 3, has a cap 8 fastened thereto or made an integral part of the piece 7, and of larger diameter than the mouth of the tube. The pieces 5 and 7 are sufficiently springy and resilient to cause the cap 8 (the ordinary screw cap be-

ing removed) to bear firmly against the opening in the tube A and tightly close the same when pushed across the mouth and may be laterally slid away from the mouth there-
5 of when the contents of the tube are pushed outwardly.

What is claimed as new is:

1. An attachment for collapsible container tubes for opening and closing the tube, in
10 combination with the tube and support, comprising a resilient arm secured at one end to the under surface of the support and extending longitudinally therefrom and inclined slightly upwardly in a direction to-
15 ward the tube, an angularly bent flange continuing from the outer end of the arm, another arm pivoted to the flange for swinging movement transversely of the mouth of tube, and a relatively small plate of a di-
20 ameter sufficient to close the tube carried by the outer end of the swinging arm and adapted to be yieldingly and removably held against the mouth of the tube substantially as and for the purposes set forth.
- 25 2. A collapsible tube holder comprising in

combination a body formed from a single piece of sheet metal including a bottom, up-turned sides and lower end walls projecting therefrom and attaching portions continuing from the upper end of the bottom, 30 legs projecting from the lower end of said bottom, the lower end wall being recessed and adapted to receive the neck of a collapsible tube, when the tube is placed upon the bottom of said body, a manually oper- 35 able tube engaging and collapsing key mounted within the side wall of said body, a bracket secured to and extending from the lower end of said body, an arm pivotally connected to said bracket for swinging 40 movement transversely of the mouth of the tube and a relatively small plate of a diameter sufficient to close the tube carried by the outer end of the swinging arm and adapted to be removably held against the 45 mouth of the tube substantially as and for the purpose set forth.

In testimony whereof I have signed my name to this specification.

BEN CLIFFORD BLACKMON.
